UNITED STATES PATENT OFFICE.

JOSIAH B. GATHRIGHT, OF LOUISVILLE, KENTUCKY.

WRENCH.

1,117,026.

Specification of Letters Patent.

Patented Nov. 10, 1914.

Application filed June 20, 1913. Serial No. 774,838.

To all whom it may concern:

Be it known that I, JOSIAH B. GATHRIGHT, a citizen of the United States, residing at Louisville, in the county of Jefferson and State of Kentucky, have invented new and useful Improvements in Wrenches, of which the following is a specification.

This invention relates to certain improvements in gripping tools of that class having crossed levers and jaws so correlated that the jaws move in parallel planes while being adjusted, and in which handles are employed which are gripped while the tool is being used.

15 Nut wrenches form a leading type of hand tools of the class herein referred to and such wrenches have been selected to exemplify the present improvements: but it should be understood that it is my purpose to embody the present improvements in such hand tools, generally, as lend themselves to the utilization of the features hereinafter set forth, and hence reserve the liberty of embodying the improvements hereinafter described and claimed in hand tools other than those known specifically as nut wrenches and to all such tools in which said features may be usefully employed.

One of the important objects of the 30 present invention is to provide a tool of the class herein set forth which will be of strong, durable, neat and well balanced construction and which may be most readily and conveniently adjusted to fit different sizes of 35 articles without causing the handles to be moved so wide apart as to be not conveniently held within the grasp of the user when the jaws have been adjusted to fit the widest articles for which the tool is intended.

40 Another, and very important, object of the invention is to provide a tool of the class stated with adjusting means so located that the tool may be held and adjusted with one hand, the adjusting means being provided 45 with a finger grip located between the jaws and hand grips and being in the central longitudinal axis of the tool.

Another of the important objects of the 50 present invention is to provide a tool of the kind herein stated having an indicating means which will disclose when the jaws have been adjusted accurately to fit articles of particular diameters.

The foregoing objects of the invention 55 and others which will appear from the following description of the preferred embodiment

ment thereof are secured from the construction illustrated in the accompanying drawings, wherein:

Figure 1 is a view partly in elevation and 60 partly in section showing a nut wrench constructed in accordance with the present invention, the parts being in the position they occupy when the wrench is closed to its extreme limit; Fig. 2 is a longitudinal view on 65 a plane at right angles to that from which the device is viewed in Fig. 1; Fig. 3 is a cross section on the line 3—3 of Fig. 1; and Fig. 4 is a cross section on the line 4—4 of Fig. 1. 70

A and B designate two members, the upper or forward ends 10 and 11 of which cross each other and are pivoted together at 12. The rear or lower ends 13 and 14 of these members A and B are of channeled 75 form and so correlated that when the wrench is closed one fits within the other as shown in Figs. 1 and 3.

The parts 10 and 11 form crossed levers and the parts 13 and 14 form the handle portion of the wrench. The members A and B are so shaped as to provide a space 15 between the pivot 12 and the handle portions 13 and 14. This space receives the head 16 of right and left threaded screws 17 and 18, 80 said screws projecting laterally from the head and engaging swiveled hollow internally threaded blocks 19 and 20 respectively. Preferably, the members A and B are formed of sheet metal approximately U- 90 shaped in cross-section, throughout, and consequently the blocks 19 and 20 are employed to afford an adequately stiff threaded portion for engaging the screws 17 and 18. 85

C and D designate the jaws. These jaws 95 are formed separate from the members A and B and are pivoted to the upper or forward ends of the latter at 21 and 22 respectively. These jaws are formed with downward prolongations having elongated 100 openings 23 and 24, the said prolongations being bifurcated, as shown. Guide pins 25 and 26 extend through said openings and through the opposite walls of the members A and B. 105

The outer webs of the upper or forwardly projecting parts of the members A and B are removed, as shown at 27 and 28, in order that the jaws C and D may extend into the channeled members A and B, and said removed portions preferably extend from a 110 plane below or rearward of the guide pins

25 and 26 to the upper or forward ends of the parts 10 and 11, whereby the crossed levers are bifurcated, the limbs thereof bearing at opposite sides of the said jaws.

5 It will be noted that when the jaws are closed to their extreme limit they are in a spaced relation, the extent of their inward movement being defined by shoulders 29 and 30 at the sides of the head 16, for example, said shoulders being so arranged that they will form stops against which the edges of the members A and B will abut before the jaws have been brought into contact with each other. It also will be noted that when 10 the tool is closed, one portion, as 14, of the handle enters and closely fits within the other portion. It therefore will be seen that the jaws may be opened a considerable extent without opening the portions 13 and 14 15 to such a distance that they cannot be conveniently included within the grasp of the user. The spaced relation of the jaws C and D is preferably such as to be the same or slightly less than the diameter of the smallest nuts upon which it is intended to use the wrench.

The use of right and left threaded screws enables the wrench to be quickly adjusted and the relative arrangement of the various 30 parts is such that the wrench is well balanced and neat in its appearance. While the members A and B are preferably formed from material of channeled or U-shape form in cross section, it is apparent that they may 35 be made from material of specifically different shape, provided their portions 13 and 14 are arranged to overlap and their upper or forward portions are bifurcated or hollow to receive the prolongations from the 40 jaws.

In order that the jaws may be accurately adjusted to fit different sizes of nuts, when the sizes of the latter are known, without requiring preliminary guess work and subsequent adjustment of the jaws onto the nut, an indicating means is provided which shows accurately the distance between the

jaws in the various adjustments of the latter, and hence shows when they have been adjusted to a position to fit a particular known size of nut which it is intended to tighten or loosen. This indicating means comprises two parts, to wit, a scale 31 and a pointer 32, respectively provided on adjacent portions of the crossed levers 10 and 11. 55 The pointer is shown as a projection from the edge of the lever 10 and the scale is arranged on the lever 11 concentrically around the pivot 12.

Having now described the invention, what 60 I believe to be new and desire to secure by Letters Patent, and what I, therefore, claim, is:—

A hand tool comprising a pair of members whose rear ends terminate in handles and 65 whose forward ends are provided with crossed levers which are formed integral with said members and are pivoted to each other at the place of their intersection, jaws formed separate from said members and pivoted to the forward ends of the crossed levers, means acting upon the members to open and close the jaws said means lying in the plane intersecting the central longitudinal axes of the jaws and being provided 70 with an operating member positioned constantly in alinement with the central longitudinal axis of the tool, and means for causing the jaws to move in parallel planes while they are being opened and closed, the tool 75 having parts operatively arranged to define the inward movement of its jaws to positions in which they are spaced from each other when they have been fully closed and said handles being hollow and arranged to 80 be received one within the other when the jaws are in their last-named position.

In testimony whereof I have hereunto set my hand in presence of two subscribing witnesses.

JOSIAH B. GATHRIGHT.
